UNITED STATES PATENT OFFICE.

EMIL J. HERMAN, OF ST. LOUIS, MISSOURI, ASSIGNOR TO THE SAFETY HATCH-DOOR COMPANY, OF SAME PLACE.

SELF-CLOSING HATCHWAY.

SPECIFICATION forming part of Letters Patent No. 404,705, dated June 4, 1889.

Application filed June 26, 1888. Serial No. 278,238. (No model.)

To all whom it may concern:

Be it known that I, EMIL J. HERMAN, of the city of St. Louis, in the State of Missouri, have invented a certain new and useful Improvement 5 in Self-Closing Hatchways, of which the following is a full, clear, and exact description, reference being had to the accompanying drawings, forming part of this specification, and in which—

10 Figure I is a vertical section through a hatchway, showing part of the cage in elevation and showing also the mechanism for lifting the door in elevation. Fig. II is a similar view with the parts in different positions to that shown in Fig. I.

15 My invention relates to certain improvements in self-closing hatchways; and my invention consists in features of novelty herein-after fully described, and pointed out in the 20 claim.

25 Referring to the drawings, 1 represents a door of a hatchway 2 of an elevator-shaft, and which may be large enough to close the entire hatchway; or it may be used to close only half 30 of the hatchway, as I have shown; and another door 3, opening at right angles to the door 1, being used to close the other half of the hatchway. The door 3 is (when used) operated by the same mechanism as the door 1, 35 and I will simply describe the device for operating the door 1.

4 represents a cam on the bottom of the cage 5 of the elevator; and a like or other suitable cam would be secured to the top of the 40 cage.

45 6 represents a lever pivoted at 7 to one of the uprights 8 of the elevator-shaft or to any other suitable support, and it has an arm or crank 9, to which the upper end of a rod 10 is secured, the lower end of the rod being secured to a segment 11; as shown at 12. The 50 segment is preferably provided with projections or teeth 13 to engage a chain 14, which

is connected to the segment by one end, as shown at 15. The other end of the chain is 45 connected at 16 to the door 1. The segment 11 is pivoted and turns on a fixed pin 17, secured to one of the uprights 8 or to some other suitable fixed object. Surrounding this pin, with a number of coils, is a spring 18. (This 50 will best be seen by looking at the device for operating the door 3, as a side view is there given of it.) One end of this spring is secured to an arm 19, rigidly secured to the pin 17, preferably by a set-screw 20. The other 55 end of the spring extends outwardly some distance from the pin 17, as shown at 21, and its outer end is in line with the pin that connects the lower end of the rod 10 to the segment 11, as shown at 12. 60

The operation is as follows: When the door is closed, the pin at 12 bears against the end 21 of the spring 18, as shown in Fig. I. As the door is opened the pin at 12 leaves the end 21 of the spring, as shown in Fig. II, and does 65 not come against the end 21 again until the door is very nearly closed. Thus, when the cage leaves the door in going up or coming down, the door falls shut rapidly and without any resistance or hinderance until it is almost 70 closed. The pin at 12 then comes against the spring, which takes the rapid movement from the door and compels it to close easily and gently, to avoid slamming.

I claim as my invention—

75 In a self-closing hatchway, the combination of the door, segment, chain 14, connecting the door to the segment, rod 10, lever 6, and spring 18, having arm 21, against which the segment bears when the door has nearly reached its 80 closed position and not until then, substantially as and for the purpose set forth.

EMIL J. HERMAN.

In presence of—

JOS. WAHLE,
EDWD. S. KNIGHT.
